UNITED STATES PATENT OFFICE.

RALPH L. LEE, OF DAYTON, OHIO, ASSIGNOR TO DELCO-LIGHT COMPANY, OF DAYTON, OHIO, A CORPORATION OF DELAWARE.

REVERSIBLE MOTOR.

Application filed March 13, 1924. Serial No. 698,834.

To all whom it may concern:

Be it known that I, RALPH L. LEE, a citizen of the United States of America, residing at Dayton, county of Montgomery, State of Ohio, have invented certain new and useful Improvements in Reversible Motors, of which the following is a full, clear, and exact description.

This invention relates to a power unit which includes an electric motor and mechanism operated by the motor for automatically reversing the motor.

One of the difficulties, which the present invention seeks to overcome, is one which is apt to be encountered when the speed of the motor is relatively low. In devices used heretofore the speed of the motor may be insufficient to cause the reversing mechanism fully to complete its cycle of operation whereby the motor is reversed. The result is that the motor will stop and cannot be operated in either direction until after the reversing mechanism is manually operated, although the causes of the slow speed of the motor be removed.

One object of the present invention is to provide that the operation of reversing mechanism will either be completed by the operation of the motor or else the motor will stop while yet the reversing mechanism is in condition to cause the motor to resume operation when the conditions producing low speed or power have been removed. In other words, although the motor may be stalled, the reversing mechanism will not require manipulation before the motor can be started again.

Other objects are to improve the lubrication of the reversing mechanism and to reduce noise.

A further object is to provide improvements in apparatus for cooling the motor.

Further objects and advantages of the present invention will be apparent from the following description, reference being had to the accompanying drawings, wherein a preferred embodiment of one form of the present invention is clearly shown.

In the drawings:

Fig. 1 is a side elevation of a motor and reduction gear unit embodying the present invention.

Fig. 2 is a wiring diagram of the electrical circuits and connections employed in said motor.

Fig. 3 is a view partly in section and partly in elevation of the motor and reversing mechanism therefor.

Fig. 4 is a fragmentary sectional view taken on the line 4-4 of Fig. 3.

Fig. 5 is a top plan view of the motor with the cover removed.

Fig. 6 is a sectional view taken on the line 6-6 of Fig. 5.

Fig. 7 is a fragmentary top plan view similar to Fig. 5, but showing the brush lifting cam in the opposite position.

Fig. 8 is a view similar to Fig. 4, but showing the trip mechanism in the opposite position.

Referring to the drawings, a motor and gear housing unit represented as a whole by the numeral 20, comprises a gear housing 21 which merges into a motor end frame 22. Field frame 23 comprises laminations 24 secured between annular plates 25 and 27 by rivets 26 and non-magnetic hollow rivets 28. Studs 28, passing through rivets 28, engage tapped holes 29 in frame 22 and receive nuts 30 which bear against plate 25. A brush supporting bracket 35 is secured to plate 25 by nuts 36 which engage the ends of studs 28 which pass through the bracket 35. Bracket 35 is provided with slots 37 for receiving supports 38 which are secured by rivets 39 to a cover 40. Supports 38 are secured to bracket 35 by screws 41. Cover 40 is provided with a flaring skirt 42 which overhangs the bracket 35.

Gear housing 21 is provided with a cover 45 secured by bolts 46. Cover 45 receives a plug 47 which permits lubricant to be placed within the frame 21. Cover 45 also provides a support for a retaining pawl mechanism included in a trip mechanism, to be described, the retaining pawl mechanism being removable in assembled relation with the cover.

Field windings 50 are supported by laminations 24, and an armature 51 and a commutator 52 are mounted upon a shaft 53 which is journaled in bearings 54 and 55 provided by housing 21. A worm 56 on shaft 53 cooperates with a worm gear 57 mounted on a shaft 58 rotatably supported by frame 21.

Motor reversing mechanism.

The motor brush rigging is mounted upon the bracket 35 and is removable from the

motor in assembled relation therewith. Each of the brush arms 60, 61, and 62 is provided with parallel extending ears 60^a and 60^b, which are provided with apertures for receiving a non-conducting bushing 64 which is pivotally mounted on stud 63, carried by bracket 35. Coil spring 65 surrounds bushing 64 and one end of said spring bears against a brush arm and the other end of said spring is secured to a stud 66 carried by bracket 35.

Referring to Fig. 6 the brush arms are each provided with parallel extending ears 60^c and 60^d between which spacers 67 are located. Each spacer is held in position by a stud 68 passing through said ears and spacer. Studs 68 on arms 60, 61, and 62 rotatably carry non-conducting rollers 69, 69^a and 69^b. The brush arms are provided with semi-cylindrical portions 70, which are adapted to receive the cylindrical commutator brushes 71, 72 and 73, respectively. Caps 74 attached to the brush arms by screws 75, are provided with semi-cylindrical portions 76 for engaging brushes to clamp the same to the brush arms.

Motor stopping switch.

Brush 73, which serves as a motor switch for starting or stopping the motor, is adapted to be moved into and out of engagement with the commutator 52 by a lever 80 which is pivotally mounted on a stud 81 carried by bracket 35. The inner end of lever 80 is provided with a camming surface 82 and a notch 83. When lever 80 is moved in a clockwise direction, the camming surface 82 engages roller 69 carried by brush arm 62, thereby lifting brush 73 from the commutator 52. Upon further movement of lever 80, the roller 69 rides into the notch 83 and brush 73 is held out of engagement with the commutator 52 until the lever 80 is returned to the position shown in Fig. 5.

Bracket 35 is provided with slots 85 and 86 which receive insulating bushings 87 and 87^a, respectively. Brush leads 88 and 89 extend through bushing 87^a and are soldered to clips 90 attached to brush arms 61 and 62, respectively, by screws 91. Brush lead 91^a extends through bushing 87 and is soldered to clip 92 attached to brush arm 60 by screw 93.

Control apparatus for the reversing mechanism.

The mechanism for moving the brushes 71 and 72 with respect to commutator 52 to effect reversal of the motor includes a rotatable shaft 100 which extends from the commutator end of the motor through plate 25 and the motor field frame into the gear housing 21. Shaft 100 carries a hub 101 resting on plate 25. A brush lifting cam 102 is attached to hub 101 and is provided

with camming surfaces 103 and 104 adapted to engage the rollers 69 and 69^a carried by brush arms 60 and 61. Cam 102 is provided with curved notches 105 and 106 which are adapted alternately to receive rollers 69 and 69^a, respectively.

The reversing mechanism operates reliably with changing lengths of brushes. The mechanism is so arranged that brushes 71 and 72 are never in engagement with the commutator at the same time. When the brushes are new, the brush clearance between either of the brushes 71 and 72 and the commutator is about $\frac{1}{64}$ inch when the brush lifting cam 102 is in central position.

The trip mechanism for oscillating shaft 100 and cam 102, whereby alternately to raise and lower brushes 71 and 72 with respect to the commutator, is located within the gear housing 21 in order to receive lubrication from oil splashed in the gear housing 21. This mechanism includes a lost motion member 110, see Figs. 4 and 8, which is secured to the lower end of shaft 100 by a screw 111. Member 110 is provided with lugs 112 and 113 located at opposite ends of a curved edge 114. A trip member 115 is loosely journaled on shaft 100 adjacent member 110 and is held in position by a spacer 116 which is located adjacent a wall of the housing 21. Member 115 includes a trip pawl 120 adapted to be engaged alternately by the opposite ends of a trip pad 57^a carried by worm gear 57. Pawl 120 carries a stud 121 which is adapted to move around surface 114 of lost motion member 110 and to engage lugs 112 and 113 thereof. Member 115 includes an acorn shaped trip cam 125 having camming surfaces 126 and 127 which, with lugs 128 and 129, respectively, define notches 130 and 131 respectively. The surfaces 126 and 127 meet at a point 132.

The retaining pawl mechanism which is adapted for co-operation with the cam 125 of pawl 115, is carried by cover 45 and removable from the gear housing 21 with the cover 45 in assembled relation, and includes an arm 140 which is pivotally mounted on a stud 141 carried by cover 45. A set screw 142 prevents the stud 141 from turning. The free end of arm 140 extends adjacent the trip cam 125 and carries a roller 143. A coil spring 144 surrounds the stud 141, one end thereof bearing against the inner face of cover 45, and the other end hooked over the edge of arm 140, whereby yieldingly to maintain roller 143 in engagement with the camming surfaces 126 or 127.

Mode of operation.

Assuming that the brushes 71 and 72 and the reversing mechanism are in the positions shown in Figs. 4 and 5, to start the motor, the lever 80 is moved in a counter-clockwise direction to the position shown

in Fig. 5 whereby to cause the roller 69 on brush arm 62 to be disengaged from notch 83 and camming surface 82 on lever 80. Spring 65 will then move brush 73 into engagement with the commutator 52 whereby

5 to close the motor circuit which then is as follows: from a suitable source of current (not shown) through wire 89, brush 73, across the motor armature 51, brush 72, 10 wire 88, field winding 50^a, through wire 50 back to the source of current. The motor will then be operated in one direction of rotation.

As the motor shaft 53 drives worm gear 15 57 through worm 56 in the direction of arrow 4 in Fig. 3, the end 57^b of trip pad 57^a will engage surface 120^a of the pawl 120 causing the trip member 115 to be rotated in a counterclockwise direction to the position shown in Fig. 8. Upon rotation of member 115, stud 121 will move over surface 114 of member 110 and engage lug 113. At this time the point 132 will have been moved past the roller 143, and to the right thereof 20 as viewed in Fig. 4, so that the roller 143 has been moved over the point 132 and has engaged surface 126. At this time the point 132 has moved 8 to 10 degrees counterclockwise from its mid-position. The movement 25 of roller 143 causes lever 140 to move to store power in spring 144. It is important to note that at this instant the brushes 71 and 72 are still in the positions shown in Fig. 5, because the lost motion member 110 30 has not been moved from the position shown in Fig. 4.

After the roller 143 moves past the point 132, the energy stored in spring 144 will be released whereby the trip member 115 will 40 be actuated by the camming action produced by pressure of roller 143 upon the surface 126. Due to engagement of stud 121 with lug 113, the brush cam 102 will be moved from the position shown in Fig. 5 to that 45 shown in Fig. 7. The spring 144 is strong enough to overcome the springs 65 and will move the brush lifting cam 102 all but about 10 degrees from either of its final brush-lifting positions. However, regardless of 50 the speed of rotation of the motor, the spring 144, after once released, will impart sufficient momentum to the parts 125, 110, 100 and 102, to cause the brush lifting cam 102 to travel this last 10 degrees of its movement 55 so that roller 69^a of arm 61 will be received by the notch 106 of cam 102. After roller 69 of arm 60 is released from notch 105 of cam 102, the spring 65 of arm 60 causes the roller 69 to push against the cam 102 to assist its motion in a counterclockwise direction to complete the said 10 degrees movement. The shape and position 60 of the notches 105 and 106 are such, with respect to the cooperating rollers 69 and 69^a 65 that the rollers will be retained by the

notches until the cam 102 moves again to change the position of the brushes. Brush 71 therefore engages the commutator and brush 72 is moved away from the commutator.

The motion of the motor causes energy to be stored in spring 144, which is relatively stiff, initially, and permits the spring to be released before any brush shifting takes place. The spring 144 assisted by a spring 65 produces the brush shifting movement of cam 102. Therefore reversal of the motor is independent of the speed of the motor. If the motor power is sufficient to wind up and release the spring 144, reversal of rotation 70 will be effected. But if the motor should stall before spring 144 is released, then the position of brushes 71 and 72 will not be changed. After the cause of the stalling has been removed, the motor reversing mechanism will continue its cycle of operation. Although the speed of the motor is relatively slow, brush reversing mechanism will operate independently of the operation of the motor, when once the mechanism has 75 80 85 90 95 been started into operation.

This shifting of brushes 71 and 72 with respect to the commutator 52 will cause a reversal of rotation of the motor, and the circuit will be as follows: from the source 100 of current, through wire 89, brush 73, across the motor armature 51, brush 71, wire 91, field winding 50^b which is of opposite magnetic effect to field 50^a, wire 50, back to the source of current.

Upon reversal of direction of rotation of the motor, the trip pad 57^a will be rotated in the direction of arrow y in Fig. 8, whereupon end 57^b of pad 57^a will engage surface 120^b of pawl 120. Trip member 115 will then be moved in a clockwise direction of rotation (as viewed in Fig. 8), and stud 121 will be moved away from lug 113 on member 110, and ride over surface 114 and engage lug 112. At this instant, the point 132 will have moved to the left (as viewed in Fig. 8) of the center line joining the axes of roller 143 and shaft 100 so that roller 143 engages the surface 127 of cam 125. Thereupon spring 144 will cause roller 143 to quickly ride over surface 127 and into notch 129. This will cause, by the engagement of stud 121 with lug 112, the rotation of member 110, shaft 100 and cam 102. The cam 102 will be moved from the position shown in Fig. 7 to that shown in Fig. 5, whereby to permit brush 72 to engage the commutator 52 and to lift brush 71 out of engagement therewith for causing reversal of the motor. The raising of brush 71 is caused by surface 104 of cam 102 engaging roller 69 carried by brush arm 60, and roller 69 is received by notch 105 for holding brush 71 in disengaged position.

The trip member 115 and trip pad 57^a are 105 110 115 120 125 130

- arranged so that overthrow of the trip mechanism is prevented. For example, when the member 115 is moved to the position shown in Fig. 8, the overthrow thereof, which 5 might be caused by the momentum of the mechanism itself, would be prevented by the engagement of surface 125^a of lug 129 with surface 57^a on trip pad 57^a. When member 115 is moved to the position shown in Fig. 10, the engagement of surface 125^b of lug 128 with surface 57^a of trip pad 57^a, will prevent overthrow.

Worm gear 57 and trip pad 57^a, carried thereby, dip into the lubricant within the 15 gear housing 21 and supply sufficient lubricant to the trip pawl 115 and the retaining pawl mechanism. The location of the trip mechanism and gear connections in the gear housing 21 which is remote from the field 20 windings of the motor, reduces the liability of lubricant coming in contact with said windings and tends to reduce noise of operation.

Cooling apparatus.

The means for cooling the motor and motor mechanism includes a fan 160 located in spaced relation between the brush rigging, mounted on the ring 35, and the motor cover 30 40. Fan 160 is provided with a cup-shaped central portion 161 which is provided with slots adapted to receive fingers 165 of driving dog 163.

A plate 162 of insulating material is 35 mounted on the under side of fan portion 161 and is provided with slots to receive fingers 165. Dog 163 and plate 162 are riveted to fan portion 161 by a hollow rivet 168. A groove 169 is provided in the commutator to receive the fingers 165. The commutator end of the shaft 53 is provided with a tap hole adapted to receive a screw 164 with which the fan 160 and driving dog 40 is clamped to the motor rotor. The driving dog fingers 165 and groove 169 in commutator 52 provide a driving connection for the fan 160. The plate 162 prevents the arc, which may be caused at the brush, from entering the upper part of the motor. Fan 50 blades 166 are formed by piercing the metal on three sides and then bending portions 166 downwardly. These blades 166 are disposed at substantially right angles to the plane of the brush supporting bracket 35 so that the fan 160 will whirl the air substantially the same when operated in one direction as when operated in the opposite direction. The frame 22 is provided with 55 openings 167 through which the fan 160, upon operation, tends to draw air. The air which is drawn in through openings 167 is carried through the motor field frame and through the opening in bracket 35 adjacent the commutator. The air is whirled by the fan in the cover 40 and deflected by the flar-

ing skirt portion 42 down onto the ring 35 and through the annular opening 42^a between the edge of ring 35 and skirt 42, to the outside.

While the form of embodiment of the invention as herein disclosed constitutes a preferred form, it is to be understood that other forms might be adopted, all coming within the scope of the claims which follow.

What I claim is as follows:

1. In a motor and control therefor, in combination, a stator; a rotor; a motor reversing mechanism; a housing for the stator, rotor and reversing mechanism; an oil reservoir; and control apparatus for the reversing mechanism located within the oil reservoir, said apparatus including means actuated by said rotor and means connected with the reversing mechanism for actuating the same and adapted to be set in motion by said first means and operative independently of said first means after a predetermined movement thereof.

2. In a motor and control therefor, in combination, a stator; a rotor; a housing for the stator and rotor; an oil reservoir; a motor reversing mechanism contained by the housing and having an actuating member extending within the reservoir; and control apparatus for the reversing mechanism located within the oil reservoir and including a means operated by the rotor and a second means operatively connected with said member and set into motion by operation of the first means and then operative independently of the first means after a predetermined movement thereof.

3. In a unitary motor and control therefor, in combination, a housing providing a gear chamber and a field frame; a partition between the gear chamber and frame; a rotor located within the field frame and having a shaft extending into the gear chamber; a motor reversing mechanism located adjacent the field frame and having an actuating member extending through the partition into said gear chamber; and control apparatus located within the gear chamber including means actuated by said rotor and a second means operatively connected with said actuating member for actuating same and adapted to be set in motion by said first means and operative independently of said first means after a predetermined movement thereof.

4. In a unitary motor and control therefor, in combination, a housing providing a gear chamber and a motor frame; a partition between the gear chamber and frame; a rotor located within the frame and having a shaft extending into the gear chamber; a motor reversing mechanism located within the frame and having an actuating member extending through the partition into said gear chamber; and apparatus located within

the gear chamber including means actuated by said rotor and a second means connected with said actuating member for actuating same and adapted to be set in motion by said 5 first means and operative independently of said first means after a predetermined movement thereof.

5. In a motor and control therefor, in combination, a motor having a stator including a plurality of field windings; a rotor; commutator brushes each so connected with one of the field windings as to produce opposite magnetic effects by contact with the motor commutator; brush control apparatus for causing said brushes alternately to engage the commutator whereby the motor is periodically reversed, said apparatus including mechanism located remote from said motor having means actuated by said motor 10 and a second means having connections with the brushes for actuating the same and adapted to be set in motion by the first means and operative independently of said first mechanism means after a predetermined 15 movement thereof.

6. In a unitary motor and control therefor, in combination, a housing providing a gear chamber and a field frame, said chamber having an opening; a cover for said 20 opening; a reversing mechanism for said motor located within the frame; means carried by the cover for actuating said mechanism 25

nism; and means operated by the motor for operating said reversing mechanism actuating means.

35

7. In a unitary motor and control therefor, in combination, a housing providing a gear chamber and a motor frame, said chamber having an opening; a cover for said opening; a reversing mechanism for said motor located within the frame; means carried within the gear chamber and removable with the cover and adapted to actuate said mechanism; and means within the gear housing and operated by the rotor for operating 40 said reversing mechanism actuating means. 45

8. In a unitary motor and control therefor, in combination, a housing providing a gear chamber and a motor frame, said chamber having an opening; a cover for said opening; a reversing mechanism for said motor located within the frame; and control apparatus including means actuated by said rotor and a second means operatively connected with the reversing mechanism for 50 actuating same and adapted to be set in motion by said first means and operative independently of said first means after a predetermined movement thereof, said apparatus being located within the gear chamber and 55 removable through said opening. 60

In testimony whereof I hereto affix my signature.

RALPH L. LEE.
